FIG. 1

FIG. 3

FIG. 4

FIG. 2

FIGURE 1 is a perspective view of a tire showing my new design, it being understood that the tread pattern shown continues throughout the circumference of the tire shown in broken lines.

FIGURE 2 is an enlarged fragmentary top view of my new tread design.

FIGURE 3 is a section view as taken along line III-III of FIGURE 2, looking in the direction of the arrows.

FIGURE 4 is a section view as taken along line IV-IV of FIGURE 2, looking in the direction of the arrows.

The dominant features of my design reside in the portions shown in full lines.

I claim:

The ornamental design for a tire, substantially as shown and described.
